METHOD OF SEALING CONTAINERS

Samuel H. Berch, Beverly Hills, Calif.

Application November 30, 1939, Serial No. 306,924

1 Claim. (Cl. 226—51)

This invention relates to the packaging of materials and particularly pertains to a method and means of sealing and vacuumizing containers.

In the packaging of various products, such for example as food and the like, as disclosed in my co-pending application entitled Packing machine, Serial No. 279,150, filed June 13, 1939, it has been contemplated to utilize a flexible bag-like container having an outer lamina substantially non-stretching, said lamina carrying a coating or inner lamina of material such as that known in the trade as "Pliofilm" or "Pliolite," in both of which instances the inner surface of the container lends itself to heat sealing when contacting faces are held together under conditions of heat and pressure. When a container of this type is used in the packaging of food products, such for example as coffee, which comprises the ground coffee and associated dust-like particles, it has been found that a problem is presented in order to prevent the dust-like particles from being drawn between the surfaces to be heat sealed. It will be evident that the presence of these small particles of extraneous matter will prevent a uniform tight and homogeneous heat seal to be produced, and that as a result the vacuum seal may not be perfect and may permit the seepage of air into the container to deteriorate the product. It is the principal object of the present invention, therefore, to provide a method and means of forming, vacuumizing and sealing a package of the character described in a manner to insure that the meeting surfaces to be sealed will be free of any extraneous matter, and that when heat and pressure are applied to the surfaces a continuous homogeneous seal will result.

The present invention contemplates the provision of a mold within which a package of the type described may be placed and filled with a product to be sealed therein, thereafter creasing the mouth of the container to form seams which will afterward be folded, then releasing the crease to permit the mouth to open, then subjecting the container with its contents to a vacuum action and thereafter recreasing, heat sealing and folding the mouth of the container while the container and its contents are being subjected to vacuum action.

The invention is illustrated by way of example in the accompanying drawings, in which:

Figure 1 is a diagrammatic view in side elevation showing the sequence of operation of the present invention.

Fig. 2 is a fragmentary view in front elevation

showing the creasing means for the mouth of the container.

Fig. 3 is a view in end elevation showing the means for spreading and creasing the mouth of the bag.

Fig. 4 is a view in vertical section showing the means for folding the mouth of the container and heat sealing the same.

Fig. 5 is an enlarged view in section showing the specific construction of the heat sealing means.

Fig. 6 is a fragmentary view showing the operating mechanism for the folding members.

Fig. 7 is a view in diagram indicating the appearance of the mouth of the container in plan when it is creased.

Fig. 8 is a view in plan showing the mouth of the container and the spreading means by which the container is opened after it has been creased.

Referring more particularly to the drawings, 10 indicates a frame structure upon which a pair of sprocket shafts 11 and 12 are journaled. Mounted on these shafts are sprockets 13 and 14 which carry a series of molds 15. These molds are preferably rectangular in section and are of the general type and construction shown in my application Serial No. 279,150, filed June 13, 1939, and my application Serial No. 283,794 filed July 11, 1939. The molds 15 are also substantially rectangular in vertical section. The bag or container to be utilized in this process may for example be of the type shown in my issued patent entitled Method and means of packaging food products and the like, U. S. Patent No. 2,102,716 issued December 21, 1937. This type of container is flexible and is characterized as having a relatively non-stretching outer wall and an inner wall made of a thin sheet of "Pliofilm" or the like held to the outer wall by an intermediate layer of adhesive or a product known to the trade as "Pliolite." In some instances it may be deemed desirable to eliminate the inner layer of "Pliofilm" and use a layer of "Pliolite" directly applied to the outer wall without the use of an intermediate adhesive. It is a characteristic of both "Pliofilm" and "Pliolite" that when their surfaces are contacted under the action of heat and pressure that cohesion will take place to make a tight and leak-proof joint or seam. A structure for creating this result will be hereinafter described, and is shown in Figs. 4, 5 and 6 of the drawings.

The molds 15 are mounted upon an endless chain conveyor 16 which is led around the

sprockets 13 and 14. This successively carries the previously applied containers 17 to a filling station 18, where a product is placed within the containers, and to a station 19, where the mouth of the container is spread lengthwise. This will draw the side faces of the mouth together and will pull the end faces of the mouth outwardly so that the opposite halves of the end face at each end will be drawn tightly and end creases in the mouth will be formed.

Referring to Fig. 7 of the drawings, it will be seen that spreading fingers 20 and 21 are disposed in the mouth of the container and midway the width thereof so that the fingers will contact walls 22 and 23. The opposite side walls 24 and 25 will be also indicated by solid lines. When the spreading fingers are moved to their dotted line positions it will be seen that the mouth portion of the container will be drawn together, as indicated in dotted lines, and that an end crease 26 will occur intermediate the length of the walls 22 and 23. The structure for performing this operation is indicated particularly in Figs. 2 and 3 of the drawings, where it will be seen that the main frame 10 carries a crosshead 27 which overhangs the path of travel of the molds 10. This crosshead carries a pair of spreading fingers 20 and 21 which have a gear rack 28 formed on their faces to engage pinions 29. The pinions 29 are in turn driven by a horizontal extending gear rack 30 which is mounted upon the crosshead 27 and is here shown as connected with the arm of a bell crank. The opposite arm of the bell crank carries a roller 32 which engages an eccentric cam 33 mounted upon a cam shaft 34. The cam shaft 34 is driven in synchronism with the drive of the conveyor chain 16, which is intermittently driven.

By reference to Fig. 2 of the drawings, it will be seen that the side walls 22 and 23 are indicated in their normal dotted line position, and that when the fingers 20 and 21 are moved outwardly as driven by the rack 30 they will stretch the mouth of the container lengthwise, as indicated particularly in Fig. 7. It is to be understood that when this operation takes place the container is filled substantially to the dotted line *a* indicated in Fig. 2 of the drawings, and that the stretching and creasing of the mouth occurs above that level and also above the mouth of the mold 15. It will therefore be seen that when the mouth of the container is stretched, as indicated in Fig. 2 of the drawings, it will occur as indicated by dotted lines in Fig. 7, at which time creases 26 will be formed.

In my application Serial No. 283,794 vacuum is applied to the container when the mouth of the container has been stretched and creased and while folding and sealing action is being produced by the structure shown in Fig. 4 of the drawings. In the present instance the folding and sealing action is deferred until after the creased mouth of the container has been re-opened and vacuum applied to the container and its contents. This insures that the mouth of the package will be open prior to the vacuumizing action so that thorough vacuumization may take place. This is performed at the station 35, at which time the spreading fingers 20 and 21 have been withdrawn from the mouth of the container. It may occur that due to the character of the walls of the container they will partially spread and tend to return to their original uncreased position, as indicated by solid lines in Fig. 7, or that it will be necessary to re-

store the mouth of the container positively toward its original open position by introducing a set of pins 36 which when moved to the corners of the structure will act to spread the mouth 5 of the container to its original opened position, although they will not draw with sufficient tightness to stretch the crease 26 out of the end walls 22 and 23. With the mouth of the container re-opened the structure is then carried to a vacuum chamber 37 within which the package will be vacuumized. At said station a second bag stretching and creasing unit, such as shown in Fig. 2, occurs so that after a suitable vacuum action has been created the mouth of the container may be drawn again to its collapsed position, as indicated in dotted lines in Fig. 7. It has been found in practice that if the creases 26 have been previously made before vacuum action takes place it is much easier to fold and 10 seal the mouth of the container than if this is done for the first time immediately preceding vacuumization. After the structure has been subjected to vacuum action and the mouth of the container has been again creased along the creases 26 the folding fingers 38 and 39 move into operation. These fingers are mounted upon shafts 40 and 41 which are parallel to the sides 24 and 25 of the container and are offset therefrom. The fingers, as particularly shown in Fig. 15 30 of the drawings, are of an overall length greater than the width across the container from side wall 24 to 25, thus they will overlap each other to form a final fold and will hold the walls together as the container is heat sealed.

The finger 38 is formed with an upper inclined face 42 against which heat sealing action takes place. This inclined face continues to the free end of the finger in an upper flat face 43. An end face 44 defines the free end of the finger 40 45 50 55 60 65 70 75 80 85 90 95 100 105 110 115 120 125 130 135 140 145 150 155 160 165 170 175 180 185 190 195 200 205 210 215 220 225 230 235 on a relatively small width of seam extending lengthwise of the folded portion that the material which is rendered plastic by the action of the heat may tend to flow freely at opposite sides of the contacting faces and produce an air-tight seal at both sides of the line of contact. This insures that the seam which is formed will be strong and air-tight to hold a vacuum. After this sealing operation has been performed the vacuum action may be interrupted and the vacuum sealed package may be then removed from the mold.

It will thus be seen that by the method of sealing here disclosed it is possible to eliminate the accumulation or entrapment of extraneous matter in the seal being formed and to produce the seal in a manner to insure that heat and pressure may be applied along a seam area while permitting the materials producing cohesion to accumulate at each side of that area to form strong vacuum-tight seams.

While I have shown the preferred method of performing my invention and preferred means of practising the same, it is to be understood that various changes may be made in the combination, construction and arrangement of parts of the apparatus and the steps of the method by those skilled in the art without departing from the spirit of the invention.

Having thus described my invention, what I claim and desire to secure by Letters Patent is:

A method of vacuum sealing a bag-like package, characterized as having walls which are flexible and pliable, the inner surfaces of the walls having thereon a material which when said surfaces are pressed together under the action of heat will form a vacuum-tight joint, said method comprising placing a container in a mold with its open mouth portion extending above the level of the mouth of the mold, thereafter filling the container with a product to be packed up to the level of the mouth of the mold, then stretching the mouth of the container by applying pressure upon points on the side walls intermediate the length of said walls, whereby said side walls and the opposite side walls will be stretched and drawn together and vertical creases will be formed in the side walls against which pressure was applied, thereafter releasing said pressure whereby the mouth of the container may be opened, then applying vacuum to the container and its contents to vacuumize the same, thereafter again closing the mouth of the container between the previously formed creases, and then applying heat and pressure to said closed mouth, whereby the material coating the inner surfaces of the container will form an hermetically sealed seam.

SAMUEL H. BERCH.
